UNITED STATES PATENT OFFICE.

WALTER HARRISON, OF DEWMAINE, ILLINOIS.

MINER'S ACETYLENE-GAS LAMP.

1,113,621.

Specification of Letters Patent.

Patented Oct. 13, 1914.

Application filed November 3, 1913. Serial No. 799,011.

To all whom it may concern:

Be it known that I, WALTER HARRISON, a citizen of the United States, residing at Dewmaine, in the county of Williamson and State of Illinois, have invented a new and useful Miner's Acetylene-Gas Lamp; and I do hereby declare the following to be a full, clear, and exact description of the invention, such as will enable others skilled in the art to which it appertains to make and use the same.

This invention relates to a new and useful miner's acetylene gas lamp.

One of the objects of the invention is to provide an improved lamp of this character having two carbid chambers for the generation of gas passing into a gas chamber, one of said carbid chambers being used at a time, and while the carbid in one chamber is being used, the other chamber may be refilled or replenished. In this manner, while one carbid chamber is being refilled, there is no necessity of extinguishing the light, as there is in other miners' lamps.

In practical fields the details of construction may necessitate alterations, to which the patentee is entitled, provided the alterations fall within the scope of what is claimed.

The invention comprises further features and combination of parts, as hereinafter set forth, shown in the drawings and claimed.

In the drawings; Figure 1 is a vertical sectional view through the improved miner's acetylene gas lamp. Fig. 2 is a sectional view on line 2—2 of Fig. 1. Fig. 3 is a sectional view on line 3—3 of Fig. 1. Fig. 4 is a view similar to Fig. 3 showing the circular door 59 adjusted so that openings 57 and 62 are in registration. Fig. 5 is a view similar to Figs. 3 and 4 showing openings 56 and 61 in registration. Fig. 6 is a detail view of the means to be engaged by one of the portions or lugs 27 to hold rod 23 up.

Referring more particularly to the drawings; 1 designates the casing of the lamp having a hook 2^a, whereby the lamp may be attached to a miner's helmet or cap. This casing comprises two parts 2 and 3 connected together by the band 4 there being a gasket 5 to insure the tight joint. The part 2 is subdivided into two compartments 6 and 7, the compartment 6 adapted to contain water, while the compartment 7 constitutes a gas chamber.

The divisional plate between the com-

partments 6 and 7 is designated by the numeral 8. The divisional plate is provided with an opening 9, adjoining which is a pocket 10.

11^a designates a jet fastened in the wall of the part 2 having the usual valve (not shown). The gas from the gas chamber 7 is thoroughly cleaned as it passes through the felt 12, which gas then passes through the pocket 10, and through the jet, provided, however, the valve (not shown) is open. The gas is lighted at the small orifice 13 of the jet. The top of the part 2 is provided with an opening 14 through which the water is passed into the chamber 6, there being a plug 15 for closing the opening 14.

Tubes 16 extend from the top of the part 2 downwardly through the divisional plate 8, and through the top of the part 3. Where the tubes 16 pass through the divisional plate 8 and the top 17 of the part 3, any suitable means, such as that shown at 18 may be provided to insure the tight joint. The part 3 is subdivided by a divisional plate 19 forming two carbid chambers 20 and 21, and each of the tubes 16 extends into one of these chambers. Mounted in each tube 16 is a valve rod. Mounted upon the valve rods 22 and 23 are valves 24 and 25, for closing the lower ends of the tubes 16, and when one or the other of the rods 22 and 23 are operated so as to unseat the valves 24 and 25 water is allowed to reach the carbid in one or the other of the carbid chambers, so as to generate gas. The valves 24 and 25 are held opened by means of the springs 26, that is, when the portions 27 of the handle ends 28 of the valve rods are out of engagement with the notches 29 of the projection 30 of the top of the part 2. The springs 26 act between the shoulders 21 and the collars 32, so as to hold the valves 33 and valves 24 and 25 open, thereby allowing water which passes through the openings 34 and 35 of the tubes 16, to pass through the tubes and into the carbid chambers. However, only one set of valves is open at a time, say for instance the valve 24 and the valve 33 on the same rod 22. To close the valves 24 and 25, their respective rods are raised, so that the portion 27 will engage the notch 29 of the projection 30. The purpose of providing each valve rod with two valves, is to insure the gas from the carbid from escaping, when said valves are closed.

Extending from the top of the part 2

downwardly through the partition 8 and terminating a short distance above the top 17 of the part 3 are tubes 38 and 39 having valve rods 40 and 41, the upper ends of which 5 are threaded at 42 in the tubes 38 and 39. The lower end of the rods 40 and 41 are provided with valves 43 and 44, for closing the valve openings 45 and 46. Only one of the openings 45 and 46, say for instance, the opening 10 45, is opened at one time, so as to permit the gas to enter the gas chamber 7, and as the gas enters the chamber 7 it is cleaned or strained of dirt by felt 47. The gas in the chamber passes through the felt 12, and then 15 through the jet, where it is lighted at the small orifice.

The part 3 is provided with a bottom 49 secured between the shoulder 50 and the flange 51, as shown there being washers 53. 20 The partition 19 of the part 3 is provided with flanges 54, there being washers 55, to insure against leakage from the carbid chambers. The bottom 49 is provided with two openings 56 and 57, through which the 25 carbid may be deposited in the carbid chambers 20 and 21. The partition 19 is provided with a threaded projection 58, on which is held a circular disk door 59, by means of the small button 60, which is 30 threaded to the projection 58. This circular disk door is provided with openings 61 and 62, which are so arranged relative to the openings 56 and 57, that both of the openings 56 and 57 may be closed at one time, 35 but also so arranged that when the disk door is in a position as shown in Fig. 5, only one of the openings 56 and 57, say for instance the opening 56, is open at one time, while the other is closed, as shown in Fig. 5. A 40 guard closure or hood 64 is threaded at 65 to the lower portion of the part 3, to prevent accidental displacement of the small button 60 and the disk door. Arranged between

the disk door and the bottom 49 are washers 66 and 67, to insure against leakage of the 45 water which enters the carbid chambers for moistening the carbid.

From the foregoing it will be noted an improved practical miner's lamp has been devised, and one which has been found desirable, owing to the fact that while the carbid in one chamber is generating gas for the gas chamber, the other gas chamber may be refilled, without extinguishing the light at 50 the small orifice of the jet. 55

The invention having been set forth, what is claimed as new and useful is:—

In a device as set forth, a casing having a water chamber in the top portion, and two carbid chambers in the lower portion, and 60 a gas chamber between the carbid chambers and the water chamber, means for permitting water to pass from the water chamber into one or the other of said carbid chambers, means for controlling the gas from one 65 or the other of the carbid chambers to the gas chamber, and means for consuming the gas from the gas chamber, the bottom of the carbid chambers having openings, an adjustable disk circular door for the opening provided with openings, so arranged relative 70 to the openings of the bottom, that both openings of the bottom may be closed by the door, or only one opening at a time of the bottom may be opened, and a guard 75 threaded on the lower portion of the casing for guarding the door against accidental movement.

In testimony whereof I have signed my name to this specification in the presence 80 of two subscribing witnesses.

WALTER HARRISON.
